GUN MOUNT HAVING MULTIPOSITION
CONTROL MEANS

Samuel G. Green, Alexandria, Va., and Walter H. D'Ardenne, Jenkintown Manor, William J. Meinel, Huntingdon Valley, and Weber Devore, Horsham Township, Montgomery County, Pa., assignors, by direct and mesne assignments, to Heintz Manufacturing Company, Philadelphia, Pa., a corporation of Pennsylvania

Application April 28, 1945, Serial No. 590,782

2 Claims. (Cl. 89—136)

1

This invention relates to gun mounts for machine guns and the like. More particularly, it relates to a light anti-aircraft machine gun mount for .50 cal. machine guns, which may be quickly and easily assembled and disassembled and transported by very few men. It is a general object of the invention to provide such a mount. Some of the principles involved in the present invention are improvements of the invention defined in our copending application Serial No. 516,520, filed December 31, 1943, now Patent No. 2,404,958, granted July 30, 1946.

It is a further object of the invention to provide a light-weight anti-aircraft machine gun mount capable of being manipulated and fired by a gunner from a number of different gunner positions. To this end, the rear end of the gun cradle is provided with a firing lever and also with a pivoted extension frame having, in one position, a firing lever elevated so as to enable the gunner to fire from a standing position. Preferably, the height of the mount, including the extension frame, is less than four feet.

A further object of the invention resides in the combination of the various elements (including a goose-neck elevator), which render the mount very stable and result in more accurate fire than hitherto possible.

These and further objects of the invention will become more apparent from the following description and claims when read in conjunction with the accompanying drawings, in which:

Fig. 1 is a side elevation of a mount constructed in accordance with the invention;

Fig. 2 is a front end elevation with the gun removed;

Fig. 3 is a top plan view;

Fig. 4 is an enlarged perspective view of the base member;

Fig. 5 is a perspective view of one of the legs;

Fig. 6 is a perspective view of the elevator;

Fig. 7 is a perspective view of the cradle yoke and pintle;

Fig. 8 is an enlarged view taken on the line 8—8 of Fig. 9;

Fig. 9 is an enlarged plan view of the extension frame;

Fig. 10 is a view taken on the line 10—10 of Fig. 9; and

Fig. 11 is a detail perspective of the pivotal mounting of the extension members.

The gun mount is comprised of a base A, adapted to receive legs B. An elevator C is mounted on the base for traverse over 360°. The elevator supports a cradle yoke D and the gun

cradle E is pivotally mounted in the cradle yoke for vertical pivoting movement over a range of from substantially 30° depression to 85° elevation. The rear end of the gun cradle E has an extension frame F which carries handle grips for aiming and firing the gun G. The extension frame may be employed in the position shown in full lines in Fig. 1, or, it may be folded to the dotted line position in that figure.

10 The base A (see Fig. 4) is comprised of a base plate 10, a traversing bearing member 11, and a plurality of leg clamping sockets 12. In the drawings four of such leg sockets 12 are shown.

The leg sockets 12 are comprised of tubular members, the end portions of which are divided horizontally into a bottom clamp portion 14 and an upper clamp portion 15. These clamp portions 14 and 15 are connected by hinges 16 so that the upper clamp portion 15 may be swung upwardly. The upper clamp portion 15 is provided with a slotted flange 17. The base 10 has bolts 18 adapted to extend upwardly through the slotted flanges 17, and nuts 19 provided with tightening handles 20 are provided to secure the upper clamp portions 15 in their closed position shown in Fig. 4.

These leg sockets 12 are adapted to receive legs B, one of which is shown in Fig. 5. It will be noted that the leg is provided with an upwardly projecting stud 21 adapted to engage in the slot 22 (Fig. 4), and to center the leg in its operative position. The leg is also provided near its inner end with aligned holes 23, which, when the leg is centered in position, register with aligned holes 24 in the leg sockets 12, so that, if desired, a locking pin (not shown) may be extended through the socket and leg.

The legs are of tubular construction and are bent once to slant downwardly at a gentle angle. The outer end of each leg is provided with a downwardly projecting spade 25.

While the mount is shown as having four legs, it will of course be manifest that a lesser or greater number may be employed.

45 In Fig. 5 the leg is shown as provided with an inverted U-shaped bracket 26, the arms 27 of which have aligned holes 28. These are adapted to receive a pin 29 carried by the chain 30. This arrangement is for the purpose of locking the mount to a hand cart or the like.

The base plate 10 (Fig. 4) has a plurality of holes 31 for use, if desired, in bolting the mount to a permanent or semi-permanent foundation or the like.

55 The traversing bearing member 11 has a central

tral cylindrical bore 32, the upper edge of which is beveled as at 33. Projecting upwardly from the base plate 10 into the bore 32 is a bolt 34 for use in fastening the base to the elevator C. The traversing bearing member 11 also has an offset portion 35 provided with two vertical holes 36 and 37, the purpose of which will be described later herein.

Fig. 6 shows the elevator C as comprising a lower conical bearing portion 38 having a downwardly projecting cylindrical element 39. This element has a bore 40 (dotted lines) for receiving the bolt 34 of the base member. Extending upwardly from the conical portion 38 is an angled tubular support 41, the upper portion 42 of which is disposed parallel to but spaced forwardly from the vertical axis of the base member 10, when the parts are joined as shown in Fig. 1.

The upper edge of the conical portion 38 has a lateral lug 43 secured thereto. The lug 43 carries a spring button 44 having a pin (not shown) adapted to enter either of the holes 36 or 37 in the offset portion 35 of the base (see Figs. 4 and 6). Thus, the elevator may, if desired, be locked in two points of its 360° path in traverse.

Fig. 7 is a perspective view of the cradle yoke D. The yoke is provided with a pintle 45 which fits firmly in a central bore 46 of the upper portion 42 of the elevator, so that the cradle yoke traverses together with and as a part of the elevator. For this purpose the lower end of the pintle 45 has a circular groove 47 which is engaged by a bolt 48 threaded through the elevator wall and a projecting lug 49 thereon. The bolt 48 is provided with a tightening handle 50, as shown in Fig. 2.

The arms 51 of the yoke D have aligned openings 52 for the insertion of a trunnion pin 54 (Fig. 1) on which the cradle E pivots during its vertical movement.

The arms 51 of the yoke D also have two sets of aligned holes 2 and 4, the first being adapted to receive a cradle locking pin 56 and the latter for receiving a gun locking pin 57 (see also Fig. 2).

The cradle E, perhaps best illustrated in Figs. 1, 3, 8 and 9, is comprised of two side plates 58 and 59 disposed in spaced parallel relationship to receive a gun G therebetween. The gun is secured in position by the locking pin 57, to which reference has already been made, and which also passes through the side plates 58 and 59 of the cradle E as seen in Fig. 3. A second locking pin 60 similarly secures the rear portion of the gun G to the cradle.

At the rear the main cradle plates 58 and 59 have the parallel arms 61 and 62 (see Fig. 9) which spread laterally as at 63 and then again are parallel at their rear end portions 64 and 65. These rear end portions are braced by the transverse support 66. Secured to these rear end portions 64 and 65 are operating handles 67 and 68 which extend laterally. The handle 68 is provided with a pivoted firing lever 69 (see Fig. 10) which when depressed will fire the gun through the following mechanism.

With reference to Fig. 10, the firing lever 69 has a curved hooked element 70 which engages a lug 71 on one end of a double armed lever 72 (Figs. 8 and 9). The other end of the double armed lever 72 is connected by a link 73 to a triangular plate 74 which is pivoted as at 75 to a bracket 76 rigid with the cradle. The bracket also supports a trigger control mechanism 77

having an actuating lug 78 which is connected by a link 79 to the triangular plate 74. The trigger control mechanism 77 has a lug (not shown) which engages the firing mechanism of the gun.

It should be clear that depression of the firing lever 69 will pivot the double armed lever 72, moving the link 73 downwardly, pivoting the triangular plate 74, thus pulling link 79 to the rear (Fig. 8). This action results in drawing the actuating lug 78 of the trigger control mechanism 77 rearwardly and firing the gun.

An important feature of the invention resides in the extension frame F.

The extension frame F is mounted at the rear end of arms 64 and 65. It is comprised of the extension members 80 and 81 disposed in parallel relationship and joined near their outer ends by a transverse support 82. The extension members 80 and 81 are provided at their outer ends with lateral hand grips 83 and 84, and a pivoted firing lever 85 is disposed adjacent to hand grip 84 (see Fig. 10).

The firing lever 85 is connected by a rod 86 to the double armed lever 72 so that actuation of the firing lever 85 will pivot the double armed lever 72 to fire the gun, in the same manner as firing lever 69 described hereinbefore.

The extension frame F is employed for firing primarily when it is in upright position as shown in Figs. 1, 2 and 10, but it may be swung into inoperative position beneath the cradle because of pivoting arrangement which will now be described.

The rear ends of the arms 64, 65 are each provided with a vertical projection 88 (see Fig. 11). The extension members 80 and 81 are tubular and their lower ends are slotted longitudinally as shown in Fig. 11. The lower ends of the extension members 80 and 81 are pivoted as at 89 to the arms 64 and 65 respectively in such manner that the projections 88 are straddled by the slotted ends of the extension members. When the extension members are in the position shown in Fig. 10, the slot will be seen to accommodate the full extent of the vertical projection 88 on the arm 65. To retain the extension frame in such position, the extension members are each provided with a tubular sleeve 90 which is slidable in a longitudinal direction and which, in the position shown in Fig. 10, will prevent the extension members 80, 81 and the frame F as a whole from pivoting, thus securing it in upright position.

When it is desired to swing the extension frame F to its inoperative position (shown in dotted lines in Fig. 1), the tubular sleeves 90 are slid upwardly above the projections 87 and 88, and the extension frame F may then be pivoted rearwardly, downwardly, and underneath the cradle. It may be secured in such inoperative position by spring catches 91 (Fig. 1) carried by the sides of the cradle and which engage the extension members 80 and 81.

It will be noted that a machine gun mount constructed in accordance with the invention is a versatile instrument. With the mount on flat ground and with the extension handles in an upright position the gun may be fired with the gunner in standing position, or in a squatting position. Moreover, if a circular trench is dug for the gunner around the mount, the gun may be fired either by the firing lever at the rear of the cradle or by the firing lever at the free end of the extension frame, depending on the elevation of the gun barrel.

Because of the particular arrangement of the parts the mount has excellent stability and the fire consequently is very accurate, particularly when fired by the firing lever on the extension frame.

Moreover, it will be appreciated from the disclosure made that the mount is easily disassembled so that the base, the legs, the elevator, the yoke and the cradle may be separately transported.

We claim:

1. In a gun mount, the combination of a cradle for cooperation with a gun mounted on said mount, an extension frame pivotally mounted on the rear end of the cradle, firing means mounted on said extension frame, means operatively connecting said firing means with the firing mechanism of the gun, means releasably securing said extension frame in an upright position with respect to said cradle, and means releasably securing said extension frame in a position in which it is disposed beneath the cradle.

2. A gun mount for machine guns and the like, comprising a gun cradle, an extension frame secured to the rear end of said cradle, said extension frame being pivotally mounted for movement from an upright firing position to a position beneath said cradle, means releasably securing said extension frame in said upright position, firing means carried by said extension frame, and means connecting said firing means with the firing mechanism of a gun mounted in said cradle, said extension frame including two parallel tubular members connected by a cross member, the pivotal mounting for said extension frame being located at one end of said tubular members, said

tubular members adjacent the pivotal mounting being slotted longitudinally, a pair of upright elements carried by the cradle at the rear and disposed to be engaged in said slotted portions of said tubular members when the extension frame is in upright position, a slideable sleeve on each of said tubular members for enclosing said slotted portions and the engaged upright elements when the extension frame is in upright position, manipulating handle grips secured to the rear end of the cradle and rearwardly of the gun, a firing lever disposed adjacent to one of said handle grips, manipulating handle grips mounted on the free end of said extension frame and extending laterally therefrom, said firing means on said extension frame comprising a firing lever disposed adjacent to one of the manipulating handle grips on said extension frame.

20 SAMUEL G. GREEN.
